UNITED STATES PATENT OFFICE.

CHARLES TOOLEY, OF OMAHA, NEBRASKA.

COLLAR-FASTENER.

1,148,204.

Specification of Letters Patent. Patented July 27, 1915.

Application filed June 9, 1914. Serial No. 844,005.

To all whom it may concern:

Be it known that I, CHARLES TOOLEY, a citizen of the United States, residing at Omaha, in the county of Douglas and State 5 of Nebraska, have invented a new and useful Collar-Fastener, of which the following is a specification.

The invention relates to improvements in collar fasteners for securing the back of a 10 collar to the neck band of a shirt.

The object of the present invention is to improve the construction of devices for securing the back of a collar to the neck band of a shirt and to provide a simple, practical, and inexpensive collar fastening device, of strong and durable construction, adapted to dispense with the use of a back collar button and eliminate the chafing and rubbing of the neck of the wearer incident to the use 20 of such a collar button, and capable of being manipulated with greater ease than a collar button and of securely fastening a collar to the neck band of a shirt.

A further object of the invention is to 25 provide a collar fastening device of this character which will not injure the button hole of the neck band of a shirt like a collar button, or produce any pressure on the neck of the wearer.

With these and other objects in view the invention consists in the construction and novel combination of parts hereinafter fully described, illustrated in the accompanying drawing, and pointed out in the claim appended hereto, it being understood that various changes in the form, proportion, size 35 and minor details of construction, within the scope of the claim, may be resorted to without departing from the spirit or sacrificing any of the advantages of the invention.

In the drawings:—Figure 1 is a rear elevation of a collar equipped with a fastening device constructed in accordance with this 45 invention, the collar being partly broken away and shown applied to a shirt. Fig. 2 is a perspective view of the collar. Fig. 3 is an enlarged sectional view on the line 3—3 of Fig. 1. Fig. 4 is a detail perspective view 50 of the fastening device.

Like numerals of reference designate corresponding parts in all the figures of the drawing.

In the accompanying drawing, in which is 55 illustrated the preferred embodiment of the invention, 1 designates a collar provided at

the center of the back with a depending tab 2, preferably formed integral with the inner portion 3 of the collar by two spaced substantially vertical slits, as shown, but it may be applied to the same in the form of a separate piece or attachment, if desired. The tab consists of a narrow vertical oblong strip having straight side edges 4 and provided with a tapered or pointed lower end 5 to enable it to be readily inserted in the back button hole 6 of the neck band 7 of a shirt. The tab carries a locking piece 9 having a tapered or pointed lower portion 10 corresponding to the pointed neck 5 of the tab, and fitted against and stitched to the same, as shown at 11. The locking piece 9, which fits flat against the tab, has its upper portion free to form a retaining flap 12, which, after the tab has been passed through the button hole of the neck band, is adapted to engage with the outer portion thereof. The tab and the retaining flap form a crotch in which the lower edge or portion of the neck band is confined, whereby the collar is securely fastened to the neck band.

The locking device is arranged in the recess or cut away portion 13 of the collar and presents smooth flat inner and outer surfaces, and does not interfere with the free sliding of a neck tie through the collar. The recess 13 of the inner portion of the collar has straight side edges throughout substantially the entire length of the recess, the corners being rounded at the bottom of the recess, as shown. As the tab forms an upwardly projecting neck band engaging portion which is arranged within the periphery of the tab, and as the locking piece does not increase the width of the pointed tab, the neck band engaging flap does not require any manipulation in inserting the tab in a button hole. In fact, the attached portion of the piece which forms the flap stiffens the tab and facilitates the passing of the same through the button hole. After the tab has been passed through the button hole far enough to carry the free end of the flap beyond the lower edge of the portion 14 of the neck band, the tab is drawn upward to engage the flap with the said portion 14. The collar is readily detached from the neck band by moving the tab downwardly a sufficient distance to carry the flap beyond the engaged portion, and then drawing the tab outwardly. The flap will lie flat against the tab and not interfere with the with-

drawal of the same from the button hole. The locking device is adapted to be engaged with neck bands having plain button holes, as well as those equipped with the form of neck bands shown in the accompanying drawing, and the flap will engage with the neck band at the edge of the button hole.

What is claimed is:—

A collar of the class described provided at the back of its inner portion with spaced substantially vertical slits forming a narrow oblong tab and a narrow oblong recess receiving the tab and having its side edges contiguous to the side edges of the tab substantially throughout the entire length of the recess, said tab being provided with a pointed or tapered lower end, and a tapered

locking piece conforming to the configuration of, secured to, and lying within the periphery of the tapered or pointed lower end 20 of the tab and having a free upper portion forming a flap, said tab being adapted to be passed through the button hole of a garment without manipulating the flap, and the said locking piece being relatively stiff and 25 tapered upwardly to engage the garment at the top of the button hole.

In testimony, that I claim the foregoing as my own, I have hereto affixed my signature in the presence of two witnesses.

CHARLES TOOLEY.
